[57] CLAIM

The ornamental design for a notepaper dispenser, as
shown and described.

DESCRIPTION

FIG. 1 is a top right front perspective view of a notepaper dispenser showing my new design;

FIG. 2 is a top plan view;

FIG. 3 is a left side elevational view, the right side being
a mirror image thereof; and

FIG. 4 is a front elevational view on a reduced scale,
the rear elevational view being a mirror image thereof.
The bottom of the article is conventionally flat and
unornamented.

FIG. 1

FIG. 2

FIG. 4

FIG. 3
